UNITED STATES PATENT OFFICE

IRA A. WEAVER AND JOHN STERNAMAN, OF SPRINGFIELD, ILLINOIS, ASSIGNEES
TO WEAVER MANUFACTURING COMPANY, OF SPRINGFIELD, ILLINOIS, A CORPO-
RATION OF ILLINOIS.

TIRE-CHANGING APPLIANCE.

1,341,728.

Specification of Letters Patent. Patented June 1, 1920.

Original application filed October 6, 1916, Serial No. 124,011. Divided and this application filed February 20, 1919. Serial No. 278,234.

To all whom it may concern:

Be it known that we, IRA A. WEAVER and JOHN STERNAMAN, citizens of the United States, and residents of Springfield, in the county of Sangamon and State of Illinois, have invented certain new and useful Improvements in Tire-Changing Appliances, of which the following is a specification.

Our invention pertains to machines adapted for use in the operation of transversely-split, contractible, vehicle-wheel rims and their associated tires in order to assemble or disassociate the same, the main or principal object of the invention being to provide a structure which will reduce the labor involved and eliminate the difficulties of manual actuation. A machine of the character described should have the capability of adaptation to all sizes and types of split rims employing pneumatic tires, that is to say, a mechanism of this type to be of practical use and commercial feasibility must be capable of acting as required on all of the styles and sizes of split rims commonly employed at the present time. To this end we have devised a machine combining the elements of simplicity, inexpensiveness of construction, and adaptability to the different uses required.

In order that those skilled in this art may have a full and complete understanding of the invention and its various structural and functional advantages we have illustrated in the accompanying drawings forming a part of this specification a preferred and desirable embodiment of the invention, like reference characters throughout the various views referring to the same parts or elements.

In these drawings:

Figure 1 is an elevation of the improved and novel mechanism;

Fig. 2 is a fragmentary, vertical section on an enlarged scale;

Fig. 3 is a plan view of the structure illustrating the manner of contracting a split rim to facilitate the removal of the tire casting;

Fig. 4 is a sectional detail illustrating one of the expanding and contracting jaws and its associated hook together with the screw operating mechanism; and

Fig. 5 is an end view of the portion of the structure shown in Fig. 4.

Referring to the drawings, it will be observed that the machine illustrated, representing a preferred and desirable embodiment of the invention, comprises a hollow standard 20 having an enlarged square base 21 and provided at its upper end with three, 35 stationary, radially-extending, supporting-arms 22, 23, 24 having undercut ways or grooves 25 therein as best shown in Figs. 2 to 5 inclusive. Mounted to slide within each of these three grooves or guide-ways is a jaw 26, the more or less triangular-shaped lower portion of which occupies the undercut groove in the corresponding radial arm and has a threaded aperture through its base receiving one of the three threaded members 27, 28 and 29, one of which, as is indicated, is associated with each of the arms. At its inner end, as illustrated in Fig. 2, each of such screws is provided with a bevel-pinion 30, the three of which are in mesh with a common bevel-gear 31 mounted concentrically on a hub 32 located at the center of the radial arms. At its outer end one of such threaded members, 27 for example, is provided with a crank-handle 33 by which it may be readily turned. It will be seen that, by reason of this arrangement of parts, the jaws may be manually actuated simultaneously and equally either expanding or contracting them, and that the rim clamped by such jaws is accurately centered with relation to the axis of the machine.

The portion of each jaw 26 extended upwardly from the corresponding radial-arm 20 is hollow to receive a vertically-adjustable slide-bar 34 having pivoted to its upper end a hook-member 35. As is clearly shown in Fig. 4 one edge of each slide-bar is toothed or equipped with a ratchet portion 36 to provide for its retention in the member 26 at its vertically-adjusted position. It will be readily understood that this adjustment is desirable in order to permit the appliance to accommodate rims of different widths, 130 the hooks being employed to engage the rim when necessary to effect its contraction.

A rotary sleeve or winding-drum 58 (Fig. 2) surrounds a vertical shaft 37 accommodated in the hub 32 and rests upon the latter. To the upper end of such sleeve or drum is pivoted an operating handle 59 having a tooth or dog 60 co-operating with the

circularly-notched upper face of a plate or cover 61. Secured to the sleeve 58 is a chain 62 to the outer end of which a hook 63 is fastened, the function of which in contracting the rim is best shown in Fig. 3.

The operation of the appliance is as follows:

Assuming that it is desired to remove pneumatic tire-casing A from a transversely-split rim B, the two are placed on the machine resting on the three, stationary, radiating arms 22, 23, 24, and the bars or blocks 34 having been adjusted to proper height, the three hooks 35 are swung over the upper edge of the rim and the hook 63 brought into coöperative relation with the rim near the joint therein. Thereupon, the handle or lever 59 is rotated to wind up the chain on the sleeve or drum 58 to a sufficient extent to displace or offset the ends of the rim and the handle is held in such position by the corresponding tooth of plate 61 (see Fig. 1). The crank 33 is then turned to retract or draw inwardly the plurality of jaws 26. This, through the action of hooks 35, causes a contraction of the split rim to an extent sufficient to permit the ready detachment or removal of the tire-casing therefrom. After the necessary repairs have been made, such casing or another one is returned to the rim in the position shown in a general way in Fig. 3 and, the drum and chain having been released, the crank 33 is rotated in the opposite direction causing the jaws 26 to expand or move radially outwardly equally simultaneously thus forcing or expanding the rim into proper operative relation to the tire-casing, whereupon its two ends, now in register, may be locked together in the usual way.

The tire-casing or shoe may be removed from a laterally-split rim by the use of this apparatus in a somewhat different and more expeditious manner. The rim and its casing are laid on the device in the usual way and the jaws 26 adjusted. Then the joint is broken by means of the chain 62 and its associated hook 63 as described, whereupon the operator lifts an end of the rim bringing the rim as a whole into general spiral shape from which the tire can be readily removed in the usual fashion. This spiral method of taking off the casing causes the rust to break loose easily and the operation is quicker and more expeditious than to continue contracting the rim, the latter method

under some circumstances possibly having a tendency to spring or detrimentally set the rim especially when excessive contraction is necessary by reason of a long valve-stem 60 projecting inwardly through the rim near its joint.

To those skilled in this art various modifications of the structure presented will readily suggest themselves and will obviously fall within the spirit and scope of this invention as defined by the appended claims. It is to be understood, therefore, that the invention is susceptible of a variety of embodiments all incorporating its general principles and that the invention is not limited and restricted to any particular physical embodiment.

This application is a division of our former patent application, Serial No. 124,011, tire changing machines, filed October 6, 1916.

We claim:

1. In an appliance of the character described, the combination of a support for a transversely-split rim, means to engage the rim near its joint and bring its ends into offset relation, and means to contract the rim when in such condition to facilitate the removal or application of a tire-casing, comprising a plurality of members adapted to engage the rim at intervals in its circumference, and means to simultaneously draw said members inwardly toward a common center, substantially as described.

2. In an appliance of the character described, the combination of means for separating an assembled, transversely-split, vehicle-wheel rim and its tire-casing, including a support, means in the form of a flexible element having a hook at one end for engaging the rim near the joint therein, means for lessening the effective length of such flexible element whereby the ends of the rim may be offset or displaced relatively to one another, a plurality of jaws disposed inside of the rim and having means in the form of hooks engaging said rim at intervals in the circumference thereof, and means for simultaneously moving said jaws radially inwardly to thereby contract the size of the rim and to permit the removal of the tire-casing therefrom, substantially as described.

I. A. WEAVER.
JOHN STERNAMAN.
